APPARATUS FOR PRESSING SHOES

William D. Thomas, Lynnfield, Mass., assignor
to United Shoe Machinery Corporation, Paterson, N. J., a Corporation of New Jersey

Application December 9, 1931. Serial No. 579,933

33 Claims. (Cl. 12—33)

This invention relates to improvements in apparatus for use in pressing soles and is illustrated in connection with a machine for attaching soles to shoes by the compo or cement process.

5 The illustrated machine is, except as herein otherwise described, substantially like one or both of the machines shown in the applications in the names of Milton H. Ballard, Serial No. 388,739, filed August 27, 1929, and Sidney J. Finn, Serial No. 414,516, filed December 16, 1929.

In attaching a sole to a shoe in machines of the character disclosed in the applications identified above a pad box is used to apply pressure to the sole. The pad box consists of an open-topped metal box with a vertically movable bottom, containing a hollow flexible closed bladder or pad the upper surface of which is more or less formed to suit the shape of the shoe bottom and the lower surface of which can be pressed upward when the bottom of the metal box is displaced. The pad is filled with water. The pad box is provided with pressure receiving members generally in the form of a pair of arched bails connected to the metal box and carrying plungers which can be pressed down over the ends of a shoe and sole resting on the pad to force the shoe and sole into proper contact with each other and the pad, with a so-called "preliminary pressure". This pressure, once applied, is held by a ratchet arrangement on the plungers.

The pressing machine is provided with a table with gages for properly locating the pad box on it, and at each side of the table is provided a gaging mechanism for properly locating a sole and a shoe on the pad. In the prior constructions of Ballard and Finn the gages for the toe end of the shoe were provided in two pairs, one pair contacting with the sole and shoe at the narrowing sides of the toe and the other pair contacting with the sole and shoe at the ball. The gages for the heel end of the shoe comprised a single heel end gage for the sole and one pair of heel and shoe gages arranged to contact with the sides of the heel ends of the sole and shoe. These two gage mechanisms were mounted on sliding carriages and were moved to operative positions by the pull of weighted cables.

When the sole and shoe had been successively properly positioned on the pad box by these gaging mechanisms a preliminary pressure was applied by lowering, by the operator's weight applied to a treadle, two independent levers over

the two pad box plungers respectively. These levers were loosely connected by a crossbar to which the treadle pressure was applied by a connection adjustable along the bar in order to distribute properly the treadle pressure between the two levers. As already stated, the ratchet mechanisms held the pad box plungers in the positions to which this procedure lowered them.

60 The operator then tripped a power mechanism which controlled the dropping and subsequent lifting of a heavy weight which acted to lift the movable pad box bottom to apply substantial pressure (60-70 pounds per square inch) to the sole and shoe, and means were provided for locking the movable pad box bottom in raised position before the action of the weight was terminated by lifting it back to its highest position.

65 The illustrated machine is of this character.

An object of the present invention is to improve the machine in order to enable it to handle children's shoes to better advantage. It has been found that such shoes can be advantageously treated by locating the ball portion of the shoe and sole at the same place on the pad, 70 irrespective of the size of the shoe, and this makes it advisable to provide for the adjustment of the rear pressure bail and for a more substantial range of longitudinal adjustment for the front pressure bail of the pad box to insure 75 that the plungers shall contact with the shoe and its last in the most advantageous locations. I have therefore provided the pressure bails with an adjusting means which, as illustrated, moves them both simultaneously toward or from that 80 locality of the pad box occupied by the ball portion of the sole, preferably with a fixed velocity ratio so that they will exert pressure in the same way on shoes of all lengths.

85 Another feature of the invention resides in the toe gaging mechanism for the sole and shoe. I have found that only one pair of gages for the sides of the foreparts of the sole and shoe are necessary in the case of small shoes, engaging the shoe and sole at about the tip line. In 90 accordance with the invention I have provided a toe end gage which was not present in the prior Ballard and Finn constructions. I have also provided means for locking the gage carrying carriage against movement toward the shoe 95 operated by contact of this toe end gage with the sole, and in accordance with another important feature of the invention I have provided means for locking the toe end gage against any 100 backward movement under the pressure of the 105

shoe as the operator places it on the sole and pushes it forward into contact with the toe end gage.

The heel gaging mechanism shown herein is identical with that shown in the Finn application.

Another important feature of the invention resides in the mechanism for applying the preliminary pressure. Obviously, the pad box 10 plungers must descend farther to reach effectively a small shoe than they must to reach a large one, and I have therefore provided means for increasing the initial movement of the preliminary pressure applying levers as compared with the treadle movement which produces it. In the illustrated machine a wedge is provided which is drawn automatically into the connection between the treadle and the pressure applying levers to shorten this connection, and which so operates until the accumulated pressure has generated sufficient friction to prevent further sliding, when the mechanical advantage of the system becomes fixed. During the sliding of the wedge the mechanical advantage is of course lower.

These and other features of the invention comprising certain combinations and arrangements of parts will be apparent from the following description of a preferred embodiment of the invention shown in the drawings, in which

Fig. 1 is a front elevation;

Fig. 2 is a plan;

Fig. 3 is a plan detail of the toe gaging mechanism in inoperative position;

Fig. 4 is a plan detail of the parts shown in Fig. 3 in operative position;

Fig. 5 is a side elevation of parts shown in Fig. 4;

Fig. 6 is an enlarged detail of Fig. 5;

Figs. 7 and 8 are details;

Fig. 9 is a side elevation of the preliminary pressure mechanism;

Fig. 10 is a detail thereof;

Fig. 12 is a side elevation of the pad box;

Fig. 13 is a plan of the pad box;

Fig. 14 is a longitudinal section of the pad box;

Fig. 15 is a side elevation of the pad; and

Fig. 16 is a plan of the pad.

The pad box, as an independent and removable part of the complete apparatus, will first be described. See Figs. 12 to 16.

As shown, it comprises a metal casing or box 10 open at the top and with a bottom 12 hinged at 14. This bottom is raised as shown in Fig. 14, by a cam 16, engaging a roll 17 on the bottom 12, and pivoted at 18. The cam 16 is operated by a push arm or handle 20, as will be described.

This box 10 is occupied by a pad 22 which is made of flexible and somewhat elastic material as rubber with, if desired, a layer of fabric vulcanized into it to avoid undue stretching. This pad is filled preferably with water in quantity sufficient to fill it without distorting the shape into which it has been molded (so that its upper surface will correspond roughly to the shape of a shoe bottom). The pad 22 is not fastened in the box 10, but has a limited up-and-down movement in it, as explained in the application of S. J. Finn, Serial No. 557,496, filed August 17, 1931, which shows a pad box similar to the one disclosed herein.

The water-filled pad has a plate 24 on its toe end which forms a part of the closure clamp of the pad, and which has hooks 26 at its top. This plate 24 can slide up and down in the box 10 by virtue of holes in the front wall of the box which accommodate the projecting elements of the closure means, as described in the last-mentioned Finn application.

The pad 22 may be conveniently surmounted by a so-called blanket 28, between which and the pad 22 is a metal plate 30 which is hinged under the hooks 26 by means of a pin 32 mounted in the plate 30. The plate 30 carries a flexible flap of leather 34 which extends back of the rear edge of the plate, as described in the Finn application.

The blanket 28 will preferably be made of soft rubber and have vulcanized into its ends mask plates 36, 38 of thin flexible metal, as described in the Finn application, and for the purpose explained therein.

Means is provided, as in the Finn construction mentioned, for holding the front end of the pad and the superimposed forepart portion of the blanket normally raised to an extent sufficient to correspond to the longitudinal curvature of the bottom of a last forepart. This means, as illustrated, comprises springs 40 (Fig. 12) mounted on the box 10, with their ends under the pin 32, which is vertically movable in slots 42 in the box 10. The springs 40 normally hold the pad and blanket raised and the preliminary pressure, when applied, brings the shoe into proper contact with the blanket, and adjusts the vertical position of the blanket and pad. When the operative pressure is applied to raise the bottom 12 the hydrostatic pressure in the pad forces the front end wall of the pad outward, as well as the top wall upward, and the friction engendered between the plate 24 and box 10 holds the front end of the pad in the position in which the application of the preliminary pressure has placed it. This structure and operation are all fully described in the Finn application.

As also fully described in the Finn application, hooks 42 are molded into the blanket in proper position to engage studs 44 on the box 10 to place the blanket in proper position and limit its upward movement. The rear end of the blanket is confined by latch plates 46. The front end of the blanket is held against horizontal displacement by upstanding parts 48 of the side walls of the box 10.

The box 10 is provided on its ends with lugs 130 such as 50 to engage with gage lugs on the pressing machine, as explained in the Ballard application cited.

The novel pressure mechanism associated with the box 10 will now be described. Rods 70, one 135 on each side, are mounted to slide horizontally in lugs 72, 73 on the sides of the box. The legs of the U-shaped front pressure bail 74 are pinned to these rods so that the sliding of the rods will move the bail fore and aft. The rear ends of the bars 70 are formed as racks 76, engaging below pinion devices 77 mounted in the rear lugs 73, which pinions engage on their upper sides short racks 78 sliding in grooves in the box 10. The legs of the rear pressure bail 140 80 are pivoted on these racks 78 at 82.

The central parts of the bails 74, 80 are similar to those shown in the Ballard application. Each has a plunger 84 with a pad on the front, and an abutment on the rear bail to engage the 150

5 toe of a shoe and the cone of its last, respectively, the plungers being spring-pressed upward and held down in any position to which they may have been thrust by a ratchet device 86.

10 The rods 70 are moved in adjustment by a lever 88 pivoted at 14 and having a slot-and-pin engagement with the end of one of the rods 70. The lever 88 has a spring pin handle 90 engaging in holes 92 in a segment plate mounted on the box 10, thus holding the rods 70 in any adjusted position.

15 The pinion devices 77, as shown, comprise only a single pinion engaging both racks 76, 78, and this construction will cause equal and opposite movement of the bails 74, 80 in adjustment. It is contemplated, however, that an integral double pinion may be used, the two parts having different diameters, in case other than a 1:1 movement of the bails is desired. I have found 20 in the case of small shoes that equal movements of the bails toward and from each other are adequate to produce satisfactory work.

25 A pressing machine embodying certain features of the invention will now be described. Except as otherwise described herein, it is similar to that shown in the Ballard application cited. It consists essentially of a heavy frame 100 having a flat work table 102 for the reception of such a pad box as has been described 30 above, and the table is provided with gaging means, such as that described by Ballard for locating the pad box in a definite position on the table.

35 The machine carries to the left of the table a toe gaging mechanism and to the right of the table a heel gaging mechanism, the latter of which is identical with that shown in the first Finn application mentioned. These gaging mechanisms will now be described.

40 The toe gaging mechanism is carried by a bed 400 pivotally mounted at 401 on a bracket 402 on the main frame, the axis of the pivot 401 being horizontal. The bed 400 is in the form of an open bottomed trough with guideways 406 (Fig. 5) formed in its side walls. It is held in 45 adjusted position relatively to its pivot 401 by an expansible link 408 made in the form of a turnbuckle, and pivoted to the frame 100.

50 A gage carriage 410 is arranged to slide back and forth on the bed 400, by means of two pairs of rollers 412, 414. The inner ends of the guideways 406 are lower than the outer ends, and the front end of the carriage 410 drops a little as the rollers 414 fall down over a hill 416 connecting 55 the outer and inner portions of the guideway.

55 The carriage 410 has mounted on it a spaced cover plate 418 fastened above it by four screws 420, 422. See Figs. 3 and 4. Two gage bars 424 are pivotally mounted on the screws 420, and 60 rest on the bed of the carriage 410. They each have an upstanding pin 426 on their outer ends. Each of these pins engages in one of a pair of converging slots 428 in the inner end of a gage operating member or "banjo" 430 which is slidably mounted above the gage bars and rests on a distance piece 432. The distance piece slides over a longitudinal slot in the bed of the carriage, through which slot a pin 434, which connects the banjo to the distance piece, projects. 65 terminating in a slotted block 436, (Figs. 7 and 8), the slot 438 in which embraces the shaft 437 on which the wheels 412 are mounted. The block 436 has guide wheels 439 running against the bottom of the carriage 410. This slotted 70 block 436 is attached to a cable 440 which passes

around fixed pulleys 442, 444 (Fig. 1) and leads to an arm 446 on a shaft 448 in the frame 100. When the arm 446 is depressed, the cable 440 holds the carriage in its outward position by a pull through the slotted block 436, pin 434, banjo 430, pins 426, bars 424 and screws 420. A spring 450 connects the outer end of the banjo to the cover plate 418 through a pin 452 mounted on the plate. A cable 454 runs over a pulley 456 mounted at 401, and is attached to the shaft 437. The other end of the cable 454 carries a weight 458. The weight 458 pulls the shaft 437 normally to the inner end of the slot 438, thus pulling the carriage 410 inward; so that the weight 458 and the arm 446 thus pull against each other. The spring 450 is at this time stretched, and at a later time moves the banjo inwardly on the carriage by sliding of the block 436 over the shaft 437 when the pull of the cable 440 is slackened, to set the gage bars 424, as will be seen. The inner end of the banjo carries an upstanding pin 460 which runs in a guide slot 462 in the cover plate 418, guiding this end of the banjo when such sliding movement takes place.

80 A toe gage bar 464 is mounted to slide inwardly and outwardly on the cover plate 418. It has a guide slot 466 embracing the pin 452 and is guided at its outer end by a strap 468 on the cover plate. Its rear end contacts with a lever 470 pivoted at 472 on the cover plate, and the other end of the lever 470 has a notch 474 (Fig. 4) normally engaging a little block on the under side of a lever 476 pivoted at 478 on a lug attached to the cover plate 418. The under side of the lever 476 carries at its outer end a tooth arranged to engage in a rack 480 mounted on the bed 400 when the lever 476 is swung clockwise by a spring 482 which connects it to the lever 470. This action is normally prevented by the engagement of the notch 474 with the little block on the lever 476. When the gage bar 464 is pushed outwardly, it turns the lever 470 clockwise, releasing the notch from the block, thus permitting the lever 476 to swing into position to engage the rack 480. Such engagement prevents subsequent inward movement of the carriage 410 on the bed 400. The action just described is due, as will be seen in more detail later, to the engagement of a gage on the end of the bar 464 with the toe of a sole, as the carriage 410 slides along the bed 400 toward the sole, such engagement sliding the gage bar 464 backward on the cover plate, and causing the carriage to be locked on the bed shortly after the gage has struck the toe of the sole. The latch 474, 476 is reset when the carriage 410 is pulled outward, by engagement of the tooth on the lever 476 with a cam 483. See Fig. 3.

85 100 105 110 115 120 125 130 135 140 145 150

125 130 135 140 145 150

In some instances the operator has to settle the shoe into proper position by pressing it firmly against the toe gage, and therefore, in accordance with a feature of the invention, means is provided for locking the gage bar against further outward movement under such pressure. It will be explained later that the banjo 430 moves inwardly immediately after the carriage has been locked, by virtue of the slotted connection 437, 438 and spring 450. The banjo carries a downwardly extending pin 482* (Figs. 3 and 4) which, in the outwardly retracted position of the banjo engages one arm of a bell crank lever 484 pivoted on a screw 422. The other arm 486 of this lever is pivoted to a sliding wedge 488 having a pin-and-slot connection

with the cover plate 418. When the banjo thus slides inwardly under the pull of the spring 450, it releases the arm 484, and a spring 490 which connects a third arm of the bell crank lever to the carriage 410 swings the lever clockwise and pulls the wedge 488 in behind a pin 492 on the gage bar 464 which is thus locked against further outward movement on the carriage 410. The wedge catches it right where it is, so that there is no lost motion or displacement of the gage bar.

The gage bar 464 has a slidably adjustable block 493 (Figs. 5 and 6) on its inner end with a block 494 pivoted to it at 496, and a stop screw 498 in the block rests against a ledge 500 on the bar 464 to prevent undue downward movement of the block 494. The block 494 carries a sole gage member 502 above which is mounted a sliding toe gage 504 adjustably projected over the sole gage by an eccentric 506 operated by a handle 508.

The side gage bars 424 carry on their ends sole edge and shoe gages 510. These are similar to those described in the Ballard application mentioned and consist of a sole edge gage adjustably overhung by a shoe gage, as there described.

As stated, the heel gaging mechanism is at the same as that shown and described in the first Finn and the Ballard applications mentioned above. It is arranged generally like the toe gaging mechanism on a pivotally adjustable slideway 520. It may be briefly noted that its carriage 522 carries a heel end gage bar 524 and a pair of lever arms 526 carrying shoe positioning gages at their inner ends and also another pair of sole positioning gage carrying levers lying directly below the levers 526, the arrangement being such that when the heel end gage bar 524 is brought to rest by striking the end of the sole or the operator's thumb (in case he finds this advisable to prevent the gages from moving too far forward on the sole), the carriage 522 will be brought to rest and locked against further movement on the slideway 520 in a similar manner to that explained in connection with the toe gaging mechanism above.

The gage carrying carriage 522 is pulled inward by a cable 528 and attached weight 530 and is held in outward position by a cable 532 attached to an arm similar to the arm 446 on the shaft 448. This arm is normally latched down by a little treadle 534 located a little above a treadle 536, which is in effect the end of the arm on the shaft 448. When the latch is released the shaft 448 can turn under the pull of the weights 458, 530, allowing the toe and heel gaging mechanisms to slide toward the shoe.

Up to the time the carriages 522 and 410 are brought to rest they are eased slowly inward under the control of the operator through the treadle 536, the cables 532 and 440 being kept under tension. The cable 532 is connected to a block 538 which slides in the carriage 522 like the block 436. The block 538 is connected to the gage carrying lever arms and when pulled to its outermost position on the carriage 522 holds them spread apart. When the carriage is locked, as stated, the cable 532 is released as the operator's foot continues to rise and a spring, which has been tensioned up to this time, pulls the block 538 inward, thus operating the sole gage bar levers to bring them into contact with the sole. The operator at a later time depresses with his hand a latch lever 540,

permitting another spring to turn a latched lever 541 to operate the shoe gage carrying levers to bring them in contact with the shoe. The lever 540 also simultaneously unlatches a lever 542 permitting the withdrawal of the heel end gage member 524, through the action of a tensioned spring 544, away from the shoe.

Since the mechanism for impressing the operative pressure on the shoe is also identical with that shown in the Ballard application, it will be briefly mentioned here.

The operative pressure is impressed on the shoe by the action of a dropping weight 550 which, as fully described in the Ballard application, operates to raise the pivoted floor 12 of the pad box, thus applying a pressure of 60 or 70 pounds per square inch to the shoe. This weight is lowered under power control and raised by power and at about the time it reaches its lowermost point the cam 16 is automatically actuated by a member 552 (Fig. 2) which contacts with the operating handle 20 of the cam 16, as fully explained in the Ballard application.

The weight operating mechanism is controlled by a one revolution clutch and is tripped by a lever 554 (Fig. 2) located in the front part of the table 102.

The mechanism for impressing the preliminary pressure on the shoe will next be described. See Figs. 9, 10 and 11. A standard 600 is mounted on the frame of the machine and has independently pivoted to it on a shaft 602 two levers 604, 606 which overhang the pad box. A bar 608 having a flat face 610 is loosely mounted at its ends in these levers, which are depressed over the pad box by pushing down on the bar 608. This push is exerted by a treadle 612, which is held up in inoperative position by a spring 614 and is connected by a rod 615 to a C-shaped lever 618 pivoted on the shaft 602, with the C formation embracing the rod 608. The upper part of the C has transversely slidably mounted in it a block 620 the position of which is controlled by a rocking lever 622 mounted on a vertical shaft 624 mounted in a lug 626 on the upper arm of the C. The lever 622 is spring held down against the lug 626 so as to engender substantial friction when it moves. Two stop screws 628, 630 limit the movement of the lever by striking the upper arm of the C. The end of the lever 622 has a pin-and-slot connection with the block 620.

The slide block 620 is provided with a transverse sliding block 632, whose ribs 634 run in guides in the block 620. This block 632 is wedge-shaped, and its lower surface rests on the flat face 610. It is through this block that the C-shaped lever 618 transmits pressure to the bar 610 and levers 604, 606. The rear end of this wedge block 632 is provided with a vertical slot 636 which works on a pin 638 mounted in the U-shaped end of a lever 640 pivoted at 642 at the upper end of an extension of the upper part of the C-shaped lever. The wedge block 632 is carried back and forth transversely to its length by the adjustment of the block 620, its rear end sliding on the pin 638.

A link 644 is pivotally connected at 646 and 648 to the lever 640 and the upper end of the standard 600. The pivotal connection at 648 is a sliding one, there being a spring 650 to pull the pivot 646 toward the standard, so that normally the sleeve 652, resting on lock nuts 654, rests also against the pivot 648.

Suppose now that the treadle 612 is depressed

to pull down the rod 616 and the lever 618. As the lever 618 descends toward the plungers of the pad box, carrying with it the blocks 620, 632, the spring 650 tends to hold the lever 640 against movement as the pivot 642 swings forward and down around the center 602. The result is that the lever 640 swings counterclockwise around the pivot 646, which at first remains nearly motionless. This draws the wedge 632 back between the block 620 and the bar 608, forcing down the levers 604, 606 rapidly over the pad box. After these levers have reached the pad box plungers and have forced the pad box plungers down to effective contact with the shoe, thus forcing the shoe into the pad, the resistance to their movement increases, thus increasing the friction between the wedge 632 and block 620 and bar 608. When this friction becomes great enough the wedge ceases to slide between the block 620 and bar 608 and the spring 650 begins to yield, allowing the link 644 to slide through the pivot pin 648, as the downward motion of the C-shaped lever continues, until adequate preliminary pressure has been put on the shoe.

Thus, for the same treadle action, a considerably greater initial movement of the levers 604, 606 at low mechanical advantage is produced than in the Ballard and Finn constructions mentioned, so that when a small shoe is treated, requiring the pad box plungers to descend to a greater degree than in the case of a large shoe, the pad box plungers may be adequately depressed without danger of the treadle 612 striking the floor. In case it should do so, however, a release of the treadle will permit the parts to recover their initial positions (except that the pad box plungers are held down by their ratchets, in the positions to which they have already been forced), and on a subsequent depression of the treadle the wedge 632 will slide farther in than it did on the first depression of the treadle since the levers 604, 606 do not now strike the pad box plungers at all until later in the operation of depressing the treadle. A wider part of the wedge will therefore be used on the second depression of the treadle, and less treadle movement than before will produce the same pressure as before.

The bottom of the wedge 632 is rounded to enable it to bear on the bar 608 in any vertical orientation of the bar and the adjustment of the block 620 enables the pressure transmitted by the C-shaped lever to be distributed as desired between the levers 604, 606 as explained in the Ballard application mentioned.

The wedge 632 constitutes in effect a measuring apparatus which enables the levers 604, 606 to be brought to positions where a substantial part of the preliminary pressure begins to be exerted by a comparatively small treadle movement, leaving a considerable range of treadle movement available for the application of the major part of the preliminary pressure. In another point of view it constitutes a shortening device for the rod 616, which connects the operating member 612 with the levers 604, 606.

In using the apparatus the operator puts the pad box in proper position on the machine table by means of the gages and places a cemented sole 760 on the top surface of the pad or blanket, in what he judges to be the correct position. He then steps on the latch treadle 534 and holds his foot on the treadle 536, raising the foot slowly. The weights 458 and 530 then

pull the gaging mechanisms inward until the toe end gage 502 strikes the end of the sole. A slightly further movement of the toe gage carriage 410 operates the latch 474 and locks the carriage to its slideway at 480. Further rising of the treadle 534 loosens the cable 440 and permits the spring 450 to pull the banjo 430 inward. This moves the toe gage bars 424 toward each other and toward the toe end of the sole. As they come together they will grip the toe end of the sole between them, the overhanging shoe gage resting on the upper surface of the sole. Meanwhile the forward movement of the banjo has released the lever 484, 486 which draws the wedge 488 behind the pin 492, thus locking the toe end gage bar 464 against any further backward movement.

Simultaneously with the above-described operation, the rear end gaging mechanism has moved in toward the shoe. The end gage on the bar 524 strikes the end of the sole (or the operator's finger, if he finds it to be necessary to stop the gage carriage before this time in order to locate the gages properly), and the gage carriage is locked to its slideway as above described. As the cable 532 then slackens the side sole gages are drawn forward and together and into contact with the sole.

The operator then places the shoe 702 on the sole, pressing its toe end between the toe gages and firmly against the toe end gage 504. He then trips the lever 540 and permits the rear shoe gages to swing into contact with the shoe, thus locating the rear end of the shoe accurately on the sole.

The operator will then swing the rear pressure bail 80, which has thus far been swung to his right, out of the way, up over the shoe, and will, if necessary, by means of the lever 88, adjust the distance between the bails 74 and 80 to fit the shoe.

He then applies the preliminary pressure by stepping on the treadle 612. The C-shaped lever 618 begins to descend and to exert pressure on the levers 604, 606 which begin to descend over the pad box plungers 84. Meanwhile the wedge 632 is retracted thus in effect shortening the treadle rod 616 until the pressure on the wedge becomes great enough to arrest its sliding movement by its own friction. The operator continues to depress the treadle 612 until sufficient pressure has been imparted to the plungers to hold the shoe and sole steady on the pad box, and releases the treadle. The ratchets 86 hold the pad box plungers in their pressing position.

The operator then trips the power mechanism through the member 554 which releases the weight 550, pushing up the bottom of the pad box and putting the shoe under operative pressure. The pad box bottom is cammed against retraction from its operative position by the member 552, and the weight is then raised to its initial position. The pad box and shoe are then removed from the machine and set aside for the cement to set.

Having thus described my invention, what I claim as new and desire to secure by Letters Patent of the United States is:

1. A pressure apparatus for a shoe comprising a pad carrying member arranged to impart pressure to the bottom surface of a shoe, two pressure transmitting members mounted on the pad carrying member and arranged to overhang a shoe on said member and to impart pressure thereto at separated points, and means for ad-

justing each of said pressure transmitting members toward and from the other.

2. A pressure apparatus for a shoe comprising a pad carrying member arranged to impart pressure to the bottom surface of a shoe, two pressure transmitting members mounted on the pad carrying member and arranged to overhang a shoe on said member and to impart pressure thereto at separated points, and a single means 10 for adjusting each of said pressure transmitting members toward and from the other.

3. A pressure apparatus for a shoe comprising a pad carrying member arranged to impart pressure to the bottom surface of a shoe, two pressure transmitting members mounted on the pad carrying member and arranged to overhang a shoe on said member and to impart pressure thereto at separated points, and a single means 15 for adjusting each of said pressure transmitting members toward and from the other.

15 4. A pressure apparatus for a shoe comprising a pad carrying member arranged to impart pressure to the bottom surface of a shoe, two pressure transmitting members mounted on the pad carrying member and arranged to overhang a shoe on said member and to impart pressure thereto at separated points, and an operable connection between said pressure transmitting 20 members whereby they can be adjusted simultaneously toward and from each other longitudinally of the shoe.

25 5. A pressure apparatus for a shoe comprising a pad carrying member arranged to impart pressure to the bottom surface of a shoe, two pressure transmitting members mounted on the pad carrying member and arranged to overhang a shoe on said member and to impart pressure thereto at separated points, and a rack and pinion device operating in opposite directions 30 on said pressure transmitting members whereby they may be moved simultaneously toward and from each other.

35 6. A pressure apparatus for a shoe comprising a pad carrying member arranged to impart pressure to the bottom surface of a shoe, two slides mounted on the pad carrying member to move longitudinally of a shoe thereon, two pressure transmitting members overhanging the shoe, one mounted on each slide, and means connecting the slides for adjusting them simultaneously 40 toward and from each other.

45 7. A pressure apparatus for a shoe comprising a pad carrying member arranged to impart pressure to the bottom surface of a shoe, two slides mounted on the pad carrying member to move longitudinally of a shoe thereon, two pressure transmitting members overhanging the shoe, one mounted on each slide, and a rack and pinion device connecting the slides whereby 50 they may be moved simultaneously toward and from each other.

55 8. A pressure apparatus for a shoe comprising a pad carrying member arranged to impart pressure to the bottom surface of a shoe, two pressure transmitting members mounted on the pad carrying member and arranged to overhang a shoe on said member and to impart pressure thereto at separated points, one of said pressure transmitting members being pivotally mounted 60 on said pad carrying member, and means for adjusting each of said pressure transmitting members toward and from the other.

65 9. A pressure apparatus for a shoe comprising a pad carrying member arranged to impart pressure to the bottom surface of a shoe, two pressure transmitting members mounted on the pad carrying member and arranged to overhang a shoe on said member and to impart pressure thereto at separated points, one of said pressure transmitting members being pivotally mounted 70 on said pad carrying member, and means for adjusting each of said pressure transmitting members toward and from the other.

75 10. A pressure apparatus for a shoe comprising a pad carrying member arranged to impart pressure to the bottom surface of a shoe, two pressure transmitting members mounted on the pad carrying member and arranged to overhang a shoe on said member and to impart pressure thereto at separated points, one of said pressure transmitting members being pivotally mounted on said pad carrying member, and means for adjusting each of said pressure transmitting members toward and from the other.

members toward and from the other at a uniform velocity ratio.

9. In a shoe pressing machine, two opposed pressure imparting members, an operating member and a connection therefrom to one of said pressure imparting members whereby said pressure imparting member is moved to impress pressure on a shoe located between said pressure imparting members, and a take up means located between said operating member and 85 said pressure imparting member for continuously altering the effective length of said connection as the operating member is moved.

10. In a pressing machine, two opposed pressure imparting members, a manually operated 90 member and a connection therefrom to one of the pressure imparting members, whereby said pressure imparting member is moved to impress pressure on a shoe located between said pressure imparting members, and means for shortening the effective length of the said connection 95 as the manually operated member is moved.

11. In a shoe pressing machine, two opposed pressure imparting members, an operating member and a connection therefrom to one of 100 said pressure imparting members whereby said pressure imparting member is moved to impress pressure on a shoe located between said pressure imparting members, said connection comprising a member operable, as the operating 105 member moves, to shorten the effective length of the said connection.

12. In a shoe pressing machine, two opposed pressure imparting members, an operating member and a connection therefrom to one of 110 said pressure imparting members whereby said pressure imparting member is moved to impress pressure on a shoe located between said pressure imparting members, said connection comprising a member operable by movement of 115 the said operating member, to shorten the effective length of the said connection.

13. In a shoe pressing machine, two opposed pressure imparting members, an operating member and a connection therefrom to one of 120 said pressure imparting members whereby said pressure imparting member is moved to impress pressure on a shoe located between said pressure imparting members, and a wedge operable 125 to shorten the effective length of the said connection as the operating member moves.

14. In a shoe pressing machine, two opposed pressure imparting members, an operating member and a connection therefrom to one of said 130 pressure imparting members whereby said pressure imparting member is moved to impress pressure on a shoe located between said pressure imparting members, and a wedge operated by movement of the said connection to shorten the 135 effective length of the connection.

15. In a shoe pressing machine, two opposed pressure imparting members, an operating member and a connection therefrom to one of said pressure imparting members whereby said pressure imparting member is moved to impress pressure on a shoe located between said pressure imparting members, said connection comprising a swinging member, a wedge operatively located between the swinging member and a pressure imparting member, and means operated by the swinging of the swinging member for relatively moving the wedge and swinging member to increase the effective distance between the swinging member and the pressure imparting member. 140 145 150

16. In a shoe pressing machine, two opposed pressure imparting members, an operating member and a connection therefrom to one of said pressure imparting members whereby said pressure imparting member is moved to impress pressure on a shoe located between said pressure imparting members, said connection comprising a swinging member, a wedge operatively located between the swinging member and a pressure imparting member, and means operated by the swinging of the swinging member for relatively moving the wedge and pressure imparting member to increase the effective distance between the swinging member and the pressure imparting member.

17. In a shoe pressing machine, two opposed pressure imparting members, an operating member and a connection therefrom to one of said pressure imparting members whereby said pressure imparting member is moved to impress pressure on a shoe located between said pressure imparting members, said connection comprising a swinging member, and a sliding wedge mounted therein and connected to the frame of the machine, whereby when the swinging member moves the wedge will be slid relatively thereto to alter the effective length of the said connection.

18. In a shoe pressing machine, two opposed pressure imparting members, an operating member and a connection therefrom to one of said pressure imparting members whereby said pressure imparting member is moved to impress pressure on a shoe located between said pressure imparting members, said connection comprising a swinging member, and a sliding wedge member mounted therein and connected to the frame of the machine, whereby when the swinging member moves the wedge will be slid relatively thereto to alter the effective length of the said connection, said sliding of the wedge continuing until the pressure on the pressure imparting member increases enough to generate sufficient friction to hold the wedge against further sliding.

19. In a shoe pressing machine, two opposed pressure imparting members, an operating member and a connection therefrom to one of said pressure imparting members whereby said pressure imparting member is moved to impress pressure on a shoe located between said pressure imparting members, said connection comprising a swinging member, a wedge located between the swinging member and the pressure imparting member, and a lever fulcrumed on the wedge, and on the swinging member and having its third fulcrum normally substantially fixed, the advantage of the lever being arranged to cause the movement of the wedge to be substantially greater than the movement of the swinging member.

20. In a shoe pressing machine, two opposed pressure imparting members, an operating member and a connection therefrom to one of said pressure imparting members whereby said pressure imparting member is moved to impress pressure on a shoe located between said pressure imparting members, said connection comprising a swinging member, a wedge located between the swinging member and the pressure imparting member, and a lever fulcrumed on the wedge, and on the swinging member and having its third fulcrum located closer to the fulcrum on the swinging member than to the fulcrum on the wedge, and also resiliently

connected with the frame of the machine, whereby a movement of the swinging member causes a substantially greater movement of the wedge.

21. In a pressing machine, a pressure table, two pressure imparting members arranged to press on a shoe located between them and the table, mechanism for actuating said pressure imparting members comprising an evener device whereby the operative pressure imparted to said pressure imparting members may be arbitrarily distributed between them, an operating member for said mechanism, and a connection between said operating member and said evener device, said connection having an adjustable point of application to said evener device, and a length changing device for said connection, operable as said connection is moved.

22. In a pressing machine, a pressure table, two pressure imparting members arranged to press on a shoe located between them and the table, mechanism for actuating said pressure imparting members comprising an evener device whereby the operative pressure imparted to said pressure imparting members may be arbitrarily distributed between them, an operating member for said mechanism, and a connection between said operating member and said evener device comprising a wedge having contact with the evener device and adjustable relatively thereto to distribute the said pressure, said wedge, when so adjusted, being also movable to alter the effective length of the said connection.

23. In a pressing machine, a pressure table, two pressure imparting members arranged to press on a shoe located between them and the table, mechanism for actuating said pressure imparting members comprising an evener device whereby the operative pressure imparted to said pressure imparting members may be arbitrarily distributed between them, an operating member for said mechanism, and a connection between said operating member and said evener device comprising a swinging member, a slide mounted in said member, and a sliding wedge mounted in said slide and contacting with the evener device, said wedge being adjustable by means of the said slide to vary the said distribution of pressure, and also slidably in the said slide to vary the effective length of the said connection.

24. In a machine for pressing soles and shoes together, a sole supporting means, a gaging mechanism movable toward a sole on the supporting means, said mechanism comprising a certain member, means, rendered operative by resistance to further movement of said certain member toward the sole, to hold the gaging mechanism against further movement toward the sole, and means thereafter operable to hold said certain member against movement away from the sole.

25. In a machine for pressing soles and shoes together, a sole supporting means, a carriage movable toward a sole on the supporting means and carrying end and side gaging members, means operable by contact of the end gaging member with the sole to lock the carriage against further movement toward the sole, means then operable to cause a side gaging member to move into operative relation to the sole, and means operable by said movement to prevent movement of said end gaging member away from the sole.

26. In a machine for pressing soles and shoes together, a sole supporting means, a carriage

- movable toward a sole on the supporting means and carrying end and side gaging members movable on said carriage, means operable by movement of said end gaging member upon contact with the sole to lock the carriage against further movement toward the sole, means operating thereafter to move the side gaging member into operative position relatively to the sole, and a stop for preventing movement of the end gaging member from the sole.
27. In a machine for pressing soles and shoes together, a sole supporting means, a carriage movable toward a sole on the supporting means and carrying end and side gaging members movable on said carriage, means operable by movement of said end gaging member upon contact with the sole to lock the carriage against further movement toward the sole, means operating thereafter to move the side gaging member into operative position relatively to the sole, and a stop for preventing movement of the end gaging member from the sole.
28. In a machine for pressing soles and shoes together, a sole supporting means, a carriage movable toward a sole on the supporting means and carrying end and side gaging members, means operated by said end gaging member as it strikes the sole to lock said carriage against further movement toward the sole, a control member for said side gaging member held inoperative during movement of the carriage but released for movement upon the locking thereof, and a stop arranged to prevent movement of said end gaging member away from the sole operated by said control member.
29. In a machine for manufacturing shoes, a sole supporting means, a carriage movable toward a sole on said means, a gage member movable on the carriage and moved thereon by contact with the sole as the carriage approaches the sole, means for arresting further movement of the carriage toward the sole, operated by said movement of the gage member, and a member for locking said gage member against further movement on said carriage.
30. In a machine for manufacturing shoes, a sole supporting means, a carriage movable toward a sole on said means, a gage member movable on the carriage and moved thereon by contact with the sole as the carriage approaches the sole, means for arresting further movement of the carriage toward the sole, operated by said movement of the gage member, and a member for locking said gage member against further movement on said carriage.
31. In a machine for manufacturing shoes, a sole supporting means, a gage carrying carriage, a gage movable thereon, means urging said carriage toward a sole on said supporting means, a member movably connected with the carriage and tending to hold said carriage away from said sole, means causing movement of said movably connected member relatively to the carriage when said carriage is arrested by contact of the gage with the sole, and a stop means preventing movement of the gage on the carriage away from the sole, said stop means being rendered operable by the movement of said movably connected member.
32. In a machine for manufacturing shoes, a support for a sole, a carriage movable toward a sole on the support, an end gage movable on the carriage and arranged to lock the carriage against further movement toward the sole when said end gage is arrested in its movement with the carriage toward the sole, a side gage movably mounted on the carriage, an operating member, movable on the carriage, controlling the side gage, means acting through said operating member to control movement of the carriage toward the sole and holding said operating member at one extremity of its range of movement on said carriage, resilient means for moving said operating member toward the other extremity of its range of movement when said carriage is locked, and a stop movable in response to said movement of the operating member to prevent further movement of the end gage on the carriage when a shoe is pressed against it.
33. In a machine for manufacturing shoes, a support for a sole, a carriage movable toward a sole on the support, continuously acting means tending to move the carriage toward the sole, a member under the operator's control for resisting the action of said continuously acting means, a sliding member on said carriage to which said controlled member is connected and through which it exerts its control, thereby holding, when operative, said sliding member at one extremity of its path of movement, a gage movable on said carriage and operable through such movement to lock the carriage against further movement toward the sole when the gage contacts with the sole, means operable by further release of the controlled member by the operator to move the sliding member toward the other extremity of its path of movement, and a stop arranged to arrest further movement of the gage on the carriage rendered operable by said movement of the sliding member.
